UNITED STATES PATENT OFFICE.

NORMAN CRAIG FETTERS AND CHARLES RAYMOND RICHARDS, OF ALLIANCE, OHIO.

VACUUM-CLEANER.

1,363,859.

Specification of Letters Patent. Patented Dec. 28, 1920.

Application filed January 15, 1920. Serial No. 351,565.

To all whom it may concern:

Be it known that we, NORMAN C. FETTERS and CHARLES R. RICHARDS, citizens of the United States, and residents of Alliance, in 5 the county of Stark and State of Ohio, have invented certain new and useful Improvements in Vacuum-Cleaners; and we do hereby declare the following to be a full, clear, and exact description of the invention, such 10 as will enable others skilled in the art to which it appertains to make and use the same.

Our invention relates to an improvement in dust collectors adapted particularly for 15 use in connection with electric sweepers.

In the sweepers now in use, the dust is collected in a fabric bag, the dirt being retained and the air passing out through the interstices in the bag. Some dust also es- 20 capes in the same way and the bag after short usage becomes impregnated with dirt.

The object of our invention is to provide means whereby all the dirt and dust drawn into the cleaner is washed and deposited in 25 a receptacle from which it may be removed at intervals and it consists in the parts and combination of parts as will be more fully explained and pointed out in the claims.

In the accompanying drawing; Figure 1 30 is a view partly in elevation and partly in section of our improvement applied to a suction sweeper and Fig. 2 is a view in plan of the washer shown in Fig. 1.

In the drawings we have shown the dust 35 collector carried by and forming a part of the sweeper, but it is clearly evident that it may be either a fixed or portable structure connected to the sweeper or suction device by a flexible hose, hence we would have it 40 understood that our invention comprehends both types of apparatus.

The sweeper or suction part 5 of the apparatus may be of any approved form, preferably having a suction fan operated by a 45 motor, but the suction means may be actuated by the wheels 6 on which the suction apparatus is mounted to travel.

The receptacle in which the dust is washed and collected is provided with a throat 7, 50 connected as shown in the drawings, or by a flexible hose as explained with the suction device or sweeper 5 into which the dust and dirt laden air is forced by the suction fan or other device. This throat is preferably 55 made tapering as shown and communicates

at its restricted lower end with the duct or pipe 8, which latter forms a continuation of said throat. This duct passes downwardly and in contact with the body 9 of the washer and separator, and terminates approxi- 60 mately at the vertical center of the latter in an upwardly projecting nozzle 8^a through which the air and dirt are ejected. The washer and separator 9 is partly filled with water, the normal level of which is above the 65 top of the nozzle so that the latter and the major part of duct 8 are normally full of water.

Located within the body of the washer and separator is the sediment chamber 10, 70 constructed to snugly fit within the washer and separator 9. This chamber 10 is provided with a perforated bottom 11, and also with a depending peripheral flange 12 which rests on the lugs 13 formed on the inner face 75 of washer and separator 9 adjacent the water level, but preferably in a position to hold the perforated bottom 11 in a plane above the normal water level. The chamber 10 is also provided centrally with a vertical tube 14 80 which is of greater diameter than the diameter of duct 8. The upper end of the tube 14 is preferably adjacent the plane of the top of sediment chamber 10 and the tube passes through the perforated bottom 11, into the 85 water in the washer 9 and terminates, preferably in a plane slightly above the plane of the upper end of the nozzle 8^a.

The cover 15 is detachably secured to the upper end of the washer 9 by any approved 90 means and is provided on its under side with an inverted cone and deflector 16 located with its apex in the plane of the center of the tube 14 so that the water as it is forced up the tube strikes the apex of the 95 cone and is deflected over the upper end of the tube. This cover 15 is provided with openings 17 covered with fine mesh wire screen for the escape of the air, and with a handle 17^a by which the cover may be lifted 100 and turned for securing it in place.

In the operation of the apparatus the dust and dirt are drawn into the throat 7 with the air, which is forced by the pressure from the fan or blower through the duct 8, and 105 into and through the water or other liquid in bottom of the body 9 of the washer. The size of the duct 8 is of a diameter proportional to the air pressure so that the latter will be sufficient to force the water out of the 110

duct shortly after the air pressure is applied, the pressure being sufficient to drive the dust laden air through the water and up through the tube in the form of a spray

- 5 which striking the deflector 16 spreads and is deflected over the top of the tube and falls into the sediment chamber 10. The air carried up with the water is immediately freed and passes out through the wire screens,
- 10 which are sufficiently restricted to slow down the air. The water carrying the dirt and dust falls onto the perforated bottom of the chamber 10 which retains the solids and permits the water to drain back into the
- 15 washer 9. In this manner the liquid is used over again, and as the solids are retained in the chamber 10 it forms a filter bed through which the liquid is cleaned before passing into the washer 9. The chamber 10 is of a
- 20 size sufficient to hold all the dust collected in several weeks of ordinary sweeping and the amount collected can be readily ascertained at any time by simply removing the cover 15. The water in the washer can be replen-
- 25 ished at any time, and as the chamber 10 is removable it can be removed and cleaned as often as may be necessary.

It is evident that many slight changes might be resorted to in the relative arrangement of parts shown and described without departing from the spirit and scope of our invention, hence we would have it understood that we do not wish to confine ourselves to the exact construction and arrangement of parts shown and described.

Having fully described our invention what we claim as new and desire to secure by Letters-Patent, is:—

1. In a suction cleaner, the combination of a washer, a duct therein, the outlet end of the duct terminating in a plane below the normal water level in the washer, means for forcing the dust laden air into and through the duct and upwardly through the water in the washer, and a sediment chamber above the water compartment into which the dust is deposited and from which the water filters back into the water compartment of the washer.
- 40 2. In a suction cleaner, the combination of a washer, a duct therein, the outlet end of the duct terminating in a plane below the normal water level in the washer, means for forcing the dust laden air into and through the duct and upwardly through the water in the washer, and a sediment chamber into which the water and saturated dust are deposited, the said chamber being within the washer above the normal water level and provided with a perforated bottom.
- 50 3. In a suction cleaner, the combination of a washer, a duct therein, the outlet end of the duct terminating in a plane below the normal water level in the washer, means for forcing the dust laden air into and through

the duct and upwardly through the water in the washer, and a removable sediment chamber into which the water and saturated dust are deposited.

4. In a suction cleaner, the combination of a washer, a duct therein, the outlet end of the duct pointing upwardly and in a plane below the normal water level in the washer, means for forcing the dust laden air into and through the duct and up through the water in the washer, a sediment chamber within the washer and above the water in the latter, the said chamber being removable and perforated, a tube within said chamber and in the vertical plane of the outlet end of the duct and a deflector above the tube and in the plane of the latter for deflecting the spray into the sediment chamber.

5. In a suction cleaner, the combination of a washer, a duct therein, the outlet end of the duct pointing upwardly and in a plane below the normal water level in the washer, means for forcing dust laden air into and through the duct and up through the water in the washer, a removable chamber located within the washer and having a perforated bottom, a tube passing through the bottom of said chamber and over and in the vertical plane of the outlet end of the duct and a deflector above the upper open end of the tube for deflecting the spray into the sediment chamber.

6. In a suction cleaner, the combination of a washer, a duct therein, the outlet end of the duct pointing upwardly and in a plane below the normal water level in the washer, means for forcing dust laden air into and through the duct and up through the water in the washer, a removable sediment chamber within the washer, a vertical tube over the outlet end of the duct, a deflector over the upper end of said tube for deflecting the spray into the sediment chamber and a removable cover for the washer.

7. In a suction cleaner, the combination of a washer, a duct therein, the outlet end of the duct pointing upwardly and in a plane below the normal water level in the washer, means for forcing dust laden air into and through the duct and up through the water in the washer, a removable sediment chamber in the washer, a tube passing through the bottom of the sediment chamber, the said tube being in the vertical plane of the outlet end of the duct and of greater diameter than the latter, and a removable cover for the washer, the said cover having screened openings.

8. The combination with a suction device, of a washer carried thereby and having a throat communicating therewith through which dust laden air is forced, a duct communicating with said throat and terminating in an upturned end, which is below

130

the normal water level in the washer, and
a removable sediment chamber into which
the water and solids forced up by the air
blast are deposited, the said sediment cham-
5 ber being above the water level in the
washer, so that the water deposited in the
said chamber will filter back into the washer.

In testimony whereof we have signed this

specification in the presence of two subscrib-
ing witnesses.
